UNITED STATES PATENT OFFICE.

JOHN H. JOHNSTON, OF NEW YORK, N. Y.

DESIGN FOR A SPOON.

SPECIFICATION forming part of Design No. 20,496, dated February 3, 1891.

Application filed December 29, 1890. Serial No. 376,133. Term of patent 7 years.

To all whom it may concern:

Be it known that I, JOHN H. JOHNSTON, a citizen of the United States, residing at New York city, State of New York, have invented 5 a certain new and ornamental Design for Spoons, of which the following is a description.

The design is illustrated in the accompanying drawing, which shows a spoon having 10 a conventional bowl and stem or handle extending from it. On the end of the handle is a statuette representation of Ichabod Crane, the curious and interesting fictitious schoolmaster, whose home was in Sleepy Hollow. 15 The figure constitutes a prolongation of the stem of the spoon and represents the schoolmaster standing erect with an old-fashioned cocked hat upon his head, the hair being arranged in a queue and a book held under his 20 right arm, with the letters "N. Y." thereon. The costume is the old familiar one of the period with which the character is identified. There are the familiar "Knickerbocker" or 25 knee breeches and the long frock coat, which buttons all the way down the front, and a large pocket-flap at the side. The right foot, which is toward the observer, is incased in a low buckled shoe and the lower part of the legs in stockings. The right hand grasps the

head of a cane, which inclines toward the rear, 30 the end being behind the figure. On the face of the handle, below the figure and in relief, is an old-fashioned pipe with a long stem arranged approximately parallel with the handle, and a bowl turned up so as to be about parallel with the stem, and crossed with the pipe is a flute. The end of the handle is formed with an ornamental twist or knot which forms the ground upon which the figure stands. 35

In the drawing, A represents the bowl of 40 the spoon; B, the stem or handle extending therefrom; C, the figure of Ichabod Crane, and at D the pipe and flute are seen.

It is thought unnecessary to letter the design more discriminatingly, as its general appearance and detail are obvious from the accompanying drawing. 45

I claim as my invention and desire to secure by Letters Patent—

The design for spoons herein described and 50 illustrated.

In witness whereof I have hereunto signed my name in the presence of two subscribing witnesses.

JOHN H. JOHNSTON.
